CLOTHES HANGER

Eugenio K. Pochini, San Francisco, Calif.

Application September 7, 1948, Serial No. 48,119

2 Claims. (Cl. 223—88)

1

The present invention relates to improvements in a clothes hanger wherein an inverted bow-shaped wire bar, flattened at the approximate center thereof, has its end portions elevated, then bent back under in spaced relation forming arms, operates in conjunction with a clamp comprising a pair of crossed levers having flattened portions pivotally connected to the flattened bow portion, and also extending upwardly and downwardly from said bow with the upward portions provided with arcuate or semicircular ends arranged to hug or enclose a suspension pole or the like, to prevent accidental dropping or removal of said hanger to the detriment of neat clothes suspended therefrom.

The primary object of the present invention is to provide a new and improved clothes hanger having improved means arranged to prevent accidental or inadvertent disengagement of said hanger from its support.

Another object is to provide a new and improved device of the character set forth having improved means arranged to safety suspend a garment or the like neatly and efficiently.

A further object is to provide a new and improved device of the type described having improved means for properly and efficiently suspending one or more garments, such as a coat and trousers, or a blouse and skirt, separately and independently whereby either may easily be removed without disturbing the other.

A still further object is to provide a new and improved clothes or garment hanger of the type set forth, having a greatly simplified and economically produced construction having a maximum efficiency and an attractive appearance.

The invention comprises the details of construction and the arrangement of the several parts as disclosed in the drawings forming a part of the present application; and in which—

Fig. 1 is a slightly contracted front elevation of my improved hanger as suspended from a supporting pole; and

Fig. 2 is an enlarged, broken sectional view taken on line II—II of Fig. 1, in the direction indicated.

Referring to the drawings:

To better illustrate the application as well as construction and utility of the present improvement, the numeral 1 is used to designate a suspension pole, or the like, in cross section, such as is almost universally employed or provided in clothes closets for the convenient suspension of clothes hangers.

2

The improvement comprises an inverted bow-shaped wire bar 5 having the end portions thereof bent or turned back thereunder after forming humps or elevations 6, and with arms 7 arranged in spaced relation below said bar 5, the ends of said arms 7 being closed or closely turned back upon themselves in order to form rounded ends of said arms 7, said ends also being in spaced relation to each other.

10 The bar 5 is provided in the approximate center thereof with a flattened portion 9, upon opposite sides of which are pivotally mounted, by means of a pivot or rivet 12, flattened portions 14 of a pair of crossed levers or legs 16 extending upwardly and downwardly from said pivot 12. The upper and divergent portions of said levers 16 are again crossed and have arcuate or semicircular jaws 18 upon the upper ends thereof arranged to form a closed ring, when closed, to 15 securely enclose and engage a pole 1, thereby forming a secure clamp by means of which said bar 5 may be safely and securely suspended from said pole 1. That portion below the crossed upper portions or legs of the clamp also serve as a handle by means of which handles 21 the arcuate or semicircular jaws 18 may be separated, when said handles 21 are pressed together, as indicated in dotted lines in Fig. 1 of the drawings.

20 The lower ends of said levers below their flattened portions 14 are turned inwardly forming lateral toes or extensions 24 between which a suitable spring 26 is interposed and arranged 25 normally to retain the arcuate jaws 18 closed.

In operation:

25 A garment, such, for instance, as a man's suit, not shown, may be draped in the usual manner over the bar 5 but with the humps or elevations 6 engaging and supporting the inner sides of the shoulders of said coat, whereby the shape of 30 the same more neatly may be preserved, while a pair of trousers, also not shown, as neatly may be suspended by passing the ends of the arms 7 through the belt loops, not shown, with which trousers usually are provided. Or, a feminine blouse similarly may be draped over and neatly supported by said humps 6 while a skirt, not shown, also may be separately and independently supported by passing the ends of said arms 7 through loops, not shown, generally secured to 35 the inner side of a waist band of said skirt.

40 The garments and hanger or wire bar 5 efficiently and securely may be suspended from the pole 1 by first pressing together the handles 21 which will expand the upper arcuate or semicircular jaws 18 and separate the same suffi-

3

ciently to permit the passage of the pole 1, after which pressure upon said handles 21 is released whereby the tension of the spring 26 will operate to close and maintain the said jaws 18 in closed and engaging relation with the said pole 1, as 5 fully disclosed in full lines in Fig. 1 of the drawings, whereby accidental or inadvertent removal of a hanger from said suspension pole 1 normally may be eliminated.

It should be particularly noted that the combination of the flattened portions 14 with the flattened portion 9 of the wire bar 5 provides not only a greatly simplified construction for pivotally and efficiently connecting the suspension clamp or levers 16 with said bar 5, but also provides an attractive appearance economically produced and possessing a maximum efficiency. Also should be noted, the simplicity of operation for either releasing the jaws 18 from the pole 1, and also in replacing them in a securely attached 20 manner, whereby dropping of said hangers upon a crowded pole, easily may be avoided.

Having described my invention, I claim:

1. A clothes hanger comprising a wire bar bent to form an inverted bow-shaped bar with the 25 end portions thereof bent upwardly and also bent back under said bar in spaced relation thereto, forming arms with their ends in spaced relation, the center of said bar being flattened; a clamp comprising a pair of levers having flattened portions pivotally connected to said first flattened center, and extending upwardly and downwardly

therefrom, said upper portions having semicircular jaws arranged to form a ring, when closed, and arranged to form around a pole; and a spring arranged between said lower portions of said levers and arranged normally to hold said semicircular jaws in closed relation.

2. A clothes hanger comprising a wire bent to form an inverted bow having the central portion thereof flattened and the end portions thereof bent upwardly, forming humps, then backwardly thereunder in spaced relation thereto, with the ends of said under portions also in spaced relation; a clamp comprising a pair of levers flattened at their central portions and pivotally connected to the first flattened portion on said bar, and extending upwardly and downwardly therefrom, said upper portion of said clamp being divergent then crossed and having semicircular ends arranged to form a ring; and a spring interposed between the lower ends of said levers and arranged normally to close said semicircular ends and form a ring.
